UNITED STATES PATENT OFFICE.

FRANK ALBERT ROEBUCK, OF WEST DULWICH, ENGLAND.

PHOTOGRAPHIC SHUTTER.

SPECIFICATION forming part of Letters Patent No. 687,385, dated November 26, 1901.

Application filed February 23, 1901. Serial No. 48,422. (No model.)

To all whom it may concern:

Be it known that I, FRANK ALBERT ROEBUCK, a subject of the Queen of Great Britain and Ireland, residing at 39 Rosendale 5 road, West Dulwich, in the county of Surrey, England, have invented new and useful Improvements in Photographic Shutters, of which the following is a specification.

This invention relates to improvements in 10 photographic shutters, the object being to provide an appliance of that kind which shall be cheap and simple in construction and permit of instantaneous as well as time exposures being made. It is really a modification 15 of that class of shutters known as "rebounding" ones.

In carrying my invention into effect I proceed in or in about the following manner, making reference to the accompanying drawings, in which—

Figure 1 is a front view, and Fig. 2 a side view, of my improved shutter.

I provide a base-board *a* of suitable dimensions and having an aperture *b* and proper 25 arrangements for attaching it to the hood or tube of the lens. A shutter *c* is also provided to run up and down freely in guides *d* at each side of the board *a*, the stop *d'* preventing the shutter from running completely 30 out at the bottom of the board. At one side of the board is a lever *e*, pivoted thereto at or about the center of its length, the lower end of the lever *e* being drawn normally toward the board *a* by a suitable spring *f*. Between this lower end of the lever *e* and the 35 board is a pneumatic release-teat *g*, operated by a tube *h* and a bulb in the usual manner. At the lower end of the lever *e* is an arm *i*, projecting toward the center of the 40 width of the shutter *c*, and at the upper end of the arm is a spring-finger *j*, which points toward the center of the shutter, but of less length than the arm *i* at the lower end of the lever *e*. This spring-finger *j* is pivoted so as 45 to be movable upward, but so as not to move downward farther than into the horizontal position. A knob *k* is provided in the center of the shutter *c*, and near the bottom of the shutter is a groove *l*, in which can be 50 moved to and fro a pin *m*, which stands out-

ward beyond the arm *i* and can be pushed to either end of the grooves, as may be required. At the upper end of the base-board *a* are two elastic bands, one, *n*, being nearer the board *a* than is the other one, *o*.

55

As an instantaneous shutter the appliance is used by pushing the pin *m* as far as possible toward the center of the shutter *c* and so as to be below the arm *i*. The spring *o* is then drawn down over the knob *k*. On applying pressure to the pneumatic bulb the lower end of the lever *e* is raised by the expansion of the teat *g*, and this allows the pin *m* to pass under the arm *i* and the spring *o* to draw the shutter *c* upward. When the 65 knob *k* strikes the band *n*, the shutter *c* is impelled downward again, thus acting as an ordinary rebounding one.

When the shutter is to be used for time exposures, it is set as before, except that the 70 pin *m* is moved to the other end of the groove *l*. On pressing the bulb the shutter *c* shoots up as before, the pin *m* pressing up the finger *j* as it goes by. As the finger *j* is drawn back to its normal (horizontal) position by 75 the spring *p* directly the pin *m* has passed the shutter *c* cannot rebound below the finger *j* owing to the pin *m* being caught by the upper side of the finger, where it will remain as long as the bulb is pressed. When 80 pressure is removed from the bulb, the lower end of the lever *e* is drawn back by the spring *f*, the upper end being simultaneously raised and allowing the shutter *c* to fall and complete the exposure.

85

What I claim as my invention, and desire to secure by Letters Patent, is—

In photographic shutters, a base-board having therein a lens-aperture: guides at each side of the base-board: a shutter to run freely in the said guides: a knob on the said shutter: an elastic band for drawing up the shutter: an elastic band for impelling it downward: a lever pivoted at the center of its length to one of the said guides: a spring 90 to draw the lower end of the lever toward the base-board: a spring-finger at the upper end of the said lever: a pneumatically-operated teat between the lower end of the said lever and the base-board: an arm projecting from 100

the lower end of the lever and extending across the width of the shutter: a pin movable to and fro in a groove provided across the bottom of the shutter: and a stop on the 5 base-board to limit the downward movement of the said shutter, substantially as described.

In testimony whereof I have signed my name to this specification in the presence of two subscribing witnesses.

FRANK ALBERT ROEBUCK.
